PROTECTIVE MEANS FOR SOUND REPRODUCERS

Filed Sept. 26, 1928

Inventor:
Kirby B. Austin
by *Charles E. Tullar*
His Attorney.

UNITED STATES PATENT OFFICE

KIRBY B. AUSTIN, OF SCOTIA, NEW YORK, ASSIGNOR TO GENERAL ELECTRIC COMPANY, A CORPORATION OF NEW YORK

PROTECTIVE MEANS FOR SOUND REPRODUCERS

Application filed September 26, 1928. Serial No. 308,478.

The present invention relates to a protective means for sound reproducers of the dynamic type. Such reproducers, as is well known, are provided with an electro-magnetic field coil which is excited from a suitable source of direct current and with an actuating coil arranged to move in the field of the field coil, and are particularly adapted for reproducing sounds of great volume.

It has been found in some cases that when the field coil of such a reproducer is energized or deenergized with the operating or actuating coil connected with the output circuit of an energized electric amplifier, an undesirable repeated pistol-like report comes from the reproducer until the circuits connected therewith establish a normal operating condition. This effect on the reproducer is rather severe and may often result in injury to or dislocation of the movable sound reproducing element therein, such as the cone, in the cone-type of reproducer.

A further source of annoyance is the distortion caused by overloading the amplifier employed in connection with the sound reproducer. Like the noise occasioned by energizing and deenergizing the reproducer, it detracts from a full enjoyment of the signals being reproduced, and in the case of a large auditorium size reproducer, is very objectionable.

It is the object of the present invention to provide an improved protective means for a sound reproducer which will prevent damage thereto and will obviate the objectionable noises which tend to occur when energizing and deenergizing the same in connection with an electrical amplifying apparatus. A further feature of the invention is the provision of means which permits visual control of the distortion produced by overloading the amplifying apparatus and reproducer.

My invention will be better understood from the following description, when considered in connection with the accompanying drawing, and its scope will be pointed out in the appended claims.

The drawing is a wiring diagram of an electrical sound amplifier which is interconnected with a sound reproducer of the dynamic type and is provided with protective means embodying the invention.

Referring to the drawing, 5, 6 are amplifier tubes connected in cascade with two power or output tubes 7 and 8, in an electrical sound amplifier having input terminals 9 and output terminals 10. Terminals 10 are connected with the actuating coil 11 of a dynamic sound reproducer 12, while the input terminals 9 may be connected with any suitable electrical apparatus for producing or transmitting electrical impulses of sound frequencies.

Tubes 7 and 8 connected in parallel, as indicated by the common grid and anode connections 13 and 14. These tubes, together with the remaining tubes in the amplifier, receive anode current from a suitable source of energy, such as a rectifier 15 having positive and negative output leads 16 and 17 respectively. Negative lead 17 is continued through the amplifier as a common bus wire 18, to which is connected the cathodes of the power or output tubes 7 and 8 through a grid bias resistor 19. This is a usual selfbiasing arrangement for amplifier tubes, as is well known, the output anode current of the power tubes returning to the cathodes through this resistor.

Between the grid bias resistor 19, and the negative bus 18 or the negative supply lead for the amplifier in what may be termed the cathode return lead, is connected a resistor 20 shunted by a spark gap 21 and by a current-responsive device, such as a voltmeter 22, the last-named connection being made by extension leads 23. The voltmeter 22 may be located at any suitable operating point. It is preferably mounted adjacent to or in the same location as a suitable volume control means for the amplifier or sound reproducer.

In the present example, the volume control means for the sound reproducer and amplifier is indicated at 24. It is shown as a potentiometer connected with the input terminals 9 of the amplifier to control the

input energy received at its terminals 25, although it may be of any other suitable type and may be located at any other suitable point in the circuit.

- 5 The resistor 20 is located in the anode circuit of the output electric discharge device of the amplifier, being in the present example in the output circuit of two of such devices at a suitable point in the cathode 10 return lead, and is of such value that, with normal output anode current flowing therein, it will cause the voltmeter or indicating means to assume substantially a mid-scale position and will carry the major portion 15 of the anode current.

As is well known, variations in the anode current of an amplifier or output tube indicates overloading and distortion, and by the use of this meter connected as shown and 20 located adjacent the volume control means 24, an operator may observe any movement of the meter needle and control the volume to prevent distortion by operating the volume control means.

- 25 In any case and especially in the usual case where leads 23 or the distortion indicating circuit to the indicating meter 22 are long, an open circuit in or between these leads, as by having resistor 20 burn out or 30 open circuit would cause, a dangerously high voltage to be set up between these leads. The danger from this open circuit condition is somewhat lessened by having one end of the resistor 20 connected with 35 the negative supply bus, which is preferably grounded, as indicated but in order to fully protect lines 23, spark gap 21 is provided in shunt therewith and is preferably of a very low voltage type, arranged to puncture a 40 thin film of insulation and provide a continuous short circuit thereafter. Such types of arresters are well known and any suitable type may be employed for this purpose.

With the above described protective arrangement for controlling distortion, it will be seen that the indicating instrument, which may be any suitable current-responsive device adapted to operate in shunt with resistor 20, may be placed in any suitable location 50 in connection with any suitable control means for varying the volume of signal applied to the amplifier and reproducer, while at the same time the leads to the instrument carry only a very light current for 55 operating the meters and are protected from becoming a dangerous source of high voltage from an open circuit occurring in the indicating resistor 20.

In the present example, the field coil of 60 the reproducer, which is indicated at 26, is supplied in the usual manner from the same source as the amplifying apparatus; that is, from the rectifier 15, through field terminals 27 and 28 provided on the amplifier.

- 65 With this arrangement, the power trips of

the reproducer and the field of the reproducer build up to normal operation with the rectifier or supply unit when the latter is energized.

Terminal 28 is connected with the positive 70 side or lead 16 of the rectifier 15, through a resistor 29 and a lead 30, the resistor being provided to limit the field current to a desired value. Terminal 27 is connected with the negative side or lead 17 of the rectifier 75 through the negative bus wire 18, a portion 31 of a current-limiting resistor 32, a lead 33 and a coil 34 of a relay 35. Relay coil 34 is thus placed in series with the field winding 26 and is energized while the current is flowing through the field winding. The current flowing through the relay coil is adjusted to a desired value by passing a certain amount of the field winding current through a suitable shunt resistor, such as 80 the remaining portion of the resistor 32. This is connected in shunt with coil 34 by the addition of a lead 36 between the resistor and the coil.

The relay actuates a contact-making arm 90 37 which is normally held by a spring 38 against a contact 39 and which when the relay is energized, closes against a contact 40. Arm 37 and contact 40 are connected in series with the actuating coil of the sound 95 reproducer, in the present example being connected in the output circuit of the amplifier between the amplifier output transformer 41 and the output terminals 10.

With this arrangement the actuating coil 100 of the reproducer is connected with the output of the amplifier only after the field current is built up to a value sufficient to energize relay coil 34, at which time the amplifier is in normal operation. Thus no 105 pistol-like report of fluctuation of the moving element of the reproducer occurs in putting the apparatus into operation. Furthermore should the field winding of the reproducer or any part of the circuit connected therewith open accidentally or by actual disconnection of its leads from terminals 27 and 28, the relay coil, which is in series therewith, would instantly become deenergized and cause the output circuit 110 from the amplifier to be opened, thereby cutting off the actuating coil of the sound reproducer and preventing objectionable audible sounds.

To compensate for the loss of the field 120 load under such circumstances and to prevent an open circuit, with attendant rise in voltage across the open circuit, contact 39 is connected with lead 30 through a resistor 42, while arm 37 is connected with 125 lead 33. This arrangement places resistor 42 across or in shunt with the field and relay coil circuit when relay coil 34 is deenergized.

By connecting arm 37 with both the out- 130

put circuit of the amplifier and the low side of the field circuit, that is, lead 33, a single switching arm is sufficient to control both circuits. Any other suitable switching arrangement may however be provided for the same purpose. The relay is preferably provided with a simple single-pole double-throw switching means having a common connection with both the relay coil on its low voltage side and with the output circuit of the amplifier as shown. This arrangement, in addition, provides a ground connection for the output circuit to drain static potential therefrom.

As will be readily understood from the foregoing description, my invention has the following advantages:

1. The field circuit of the reproducer is protected against the building up of dangerously high voltage across the ends of an open circuit therein.
2. The cone or movable element of the reproducer is protected against destructive surges when the amplifier is energized.
3. Objectionable noises from the reproducer when the amplifier is energized are avoided.
4. Distortions in or overloading of the amplifier may be observed and corrected at a remote point by means which does not interfere with normal operation of the apparatus.
5. The circuit to the distortion indicating means is protected against high voltage in case of open circuit therein.

What I claim as new and desire to secure by Letters Patent of the United States, is:

1. The combination with an electrical sound amplifying apparatus embodying electric discharge devices, a sound reproducer having a field circuit and an actuating circuit, and a common source of energy for said apparatus and reproducer, of a protective means therefor comprising a resistor, a relay coil in series with said field circuit, and a switch actuated by said coil to one position for deenergizing said actuating circuit and connecting said resistor in shunt with the field circuit and to another position for closing said actuating circuit and interrupting the connection of said resistor with said field circuit.
2. The combination with an electrical sound reproducer having an actuating winding and a field winding and means for supplying said windings with energy for the reproduction of sounds, of a protective relay connected in circuit with the field winding and operable when deenergized to close a circuit in shunt to said field winding and to disconnect the actuating winding and operable when energized to interrupt the shunt circuit and complete the circuit of the actuating winding, thereby preventing disruptive movement of the repro-

ducer mechanism when energizing or de-energizing the reproducer and providing protection against the open circuit voltages of said field winding.

3. The combination with an electrical sound reproducer provided with field and actuating windings and means for energizing said windings, of a relay arranged to complete the circuit of said actuating winding only when said field winding is energized.

In witness whereof, I have hereunto set my hand this 25th day of September, 1928.
